UNITED STATES PATENT OFFICE.

HARRY L. MILLER AND RAYMOND B. FISHER, OF CHICAGO, ILLINOIS, ASSIGNORS TO THE BUDA COMPANY, OF CHICAGO, ILLINOIS, A CORPORATION.

RAILWAY-SWITCH STRUCTURE.

1,255,455.

Specification of Letters Patent.

Patented Feb. 5, 1918.

Application filed July 30, 1915. Serial No. 42,820.

To all whom it may concern:

Be it known that we, HARRY L. MILLER and RAYMOND B. FISHER, citizens of the United States, residing in Chicago, in the county of Cook and State of Illinois, have invented certain new and useful Improvements in Railway-Switch Structures, of which we declare the following to be a full, clear, and exact description, reference being had to the accompanying drawings, forming part of this specification.

The present invention has for one of its objects to provide improved means for holding down a pivoted switch point. A further object of the invention is to simplify and improve that part of the structure adjacent the pivot end of the switch. The invention consists in the features of novelty herein-after described, illustrated in the accompanying drawings and pointed out in the claims at the end of this specification.

Figure 1 is a plan view of the rear end of a structure embodying the present invention. Fig. 2 is a view in vertical section on line 2—2 of Fig. 1. Fig. 3 is a vertical cross section on line 3—3 of Fig. 1. Fig. 4 is a view in vertical section on line 4—4 of Fig. 1. Fig. 5 is a detail view in horizontal section at line 5—5 Fig. 2 through the pivot pin of the switch tongue and through its bearing in the base block.

1 and 2 designate the track rails and 3 and 4 denote the guard rails. The ends of the rails 1 and 3 are embedded in the casting operation in a cast iron base block 5 to the outer sides of which the rails 2 and 4 are united by through bolts 6, (see Figs. 1, 3) these bolts passing through the webs of the rails 2 and 4.

Within the upper face of the cast metal base block 5 is formed a cylindrical recess 5^a adapted to receive the circular heel end of the switch tongue 7 that fits snugly but revolvably within the recess of the base block. Beneath the base block 5 extends a base plate 9 that extends also from side to side of the structure beneath the base flanges of the rails 2 and 4, (see Figs. 1, 3) and to the outer flanges of these rails the base plate 9 is connected by means of rivets or bolts 10. Preferably, also, the base plate 9 is connected with the base block or casting 5 by vertically disposed rivets 10^a (see Fig. 1). By thus uniting the rails 2 and 4 to

the base block by the through bolts 6 and 5^a by the rivets or bolts 10, an extremely strong and rigid construction is secured. The base plate 9 is furnished at its side edges with holes 11 (see Fig. 1) whereby it may be conveniently spiked in place. The central portion or the base block 5 at the rear of the heel of the switch tongue extends upwardly to a point adjacent the tops of the heads of the rails 1 and 3, thus effectively bracing these rails, and it will be understood, of course, that the webs of these rails 1 and 3 will be perforated to permit the cast metal to flow therethrough in the casting operation. From the cylindrical recess in the base block 5 extends forwardly a recess or channel 12 in which rests the projecting portion of the switch tongue 7. The base block 5 is formed beneath the circular recess with a vertical cylindrical recess to receive a pivot pin 14 that depends centrally from the heel of the switch tongue 7 and is formed integral therewith. Preferably, the rear portion of the pivot pin 14 is machined or cut away, thereby leaving a slight clearance as shown at 6^a Figs. 1, 5 80 and 85 between the rear portion of the pivot pin and the adjacent face of the cylindrical recess that receives it, so that the backward and downward pressure on the pivot pin (as hereinafter explained) shall more effectively serve to hold down the front end of the switch tongue. In this pivot pin 14 is formed a notch or recess 15 preferably of the shape shown and adapted to receive a crank arm 16 that is formed on the rock 90 shaft 17 that extends transversely of the structure. The base block 5 is chambered to receive the rock shaft 17 and the rock shaft is journaled in sockets formed in the base block 5, as clearly shown in Fig. 3.

Adjacent its outer end the rock shaft 17 is provided with an arm 18 having a hole therein through which passes a bolt 19. Between the head 20 of the bolt 19 and the arm 18 is placed a coil spring 21 that exerts downward pressure on the arm 18 and through the medium of the rock shaft 17 causes the rock arm 16 to force downwardly the pivot pin 14 thereby holding the switch tongue 7 firmly to its seat and against danger of "kicking."

The bolt 19 extends through a hole in the base plate 9 and on the end of this bolt is

placed a washer and screw nut of suitable construction.

Upon the base plate 9 at one side of the structure is mounted a channel shaped box 5 25 having the ends of its side walls shaped, as at 26, to fit between the head and base of the guard rail 4, and from the side walls of this box 25 project the lugs 27 through which pass bolts 28 whereby the box 25 is 10 secured to the base plate 9. As shown, the outer wall of the box 25 is formed with an opening to receive the end of the rock shaft 17. The cover 29 for the box 25 is provided with downwardly projecting legs 30 at its 15 ends and with a flange 31 at one side, suitable openings 32 being formed in the cover to admit the fingers when the cover is to be lifted in order to permit access for the purpose of adjusting the bolt 19.

20 From the foregoing description it will be seen that when the parts are in the assembled position shown in the drawings, the pressure of the spring 21 upon the arm 18 of the rock shaft 17 will serve to cause the 25 arm 16 of this rock shaft to hold down the tongue 7 from point to heel, and as desired, the bolt 19 may be adjusted to vary the tension of the spring 21. The pressure of the rock shaft arm 16 on the inclined lower 30 surface of the recess of the pivot pin 14 not only exerts a downward pressure on the pivot pin but also a rearward pressure, thereby insuring a firm bearing of the switch tongue on the base block and also 35 against the ends of the rails 1 and 3.

By uniting the ends of the rails 1 and 3 with the cast metal base block 5, an extremely firm and rigid union of these parts is secured, and by bolting the rails 2 and 4 40 to the cast metal base block and to a base plate extending beneath such block, great strength and rigidity is given to the structure, while the loss incident to defective castings is materially less than would be the 45 case if the outer rails 2 and 4 were cast integral with the base block.

Inasmuch as the pivot pin 14 has a bearing 50 at its sides and front in the cylindrical recess formed in the cast metal base block 5 both above and below the notch or recess 15 that receives the arm 16 in the rock shaft, the pin will effectively serve to guard against any forward movement of the tongue incident to thrusts upon its heel end 55 and will guard also against any lateral rocking of the switch tongue. It will be noticed, also, that the arm 18 at the outer end of the rock shaft 17 is horizontally disposed so that the bolt 19 is in vertical position where 60 it can be most conveniently reached for ad-

justment and without unnecessarily extending the box in which the bolt is situated.

Having thus described our invention, what we claim as new and desire to secure by Letters Patent is—

65

1. In a switch structure, the combination with a suitable base or support, of a tongue having a pivot pin dependent therefrom, a bearing for said pin formed in said base or support and said pin being provided upon its front side with a recess, a rock shaft extending transversely beneath the tongue in front of said pivot pin and having an arm entering said pin recess, and means connected to said rock shaft at its outer end 75 for causing it to exert pressure upon the pivot pin of the tongue.

2. In a switch tongue, the combination with a suitable base or support, of a tongue pivotally mounted therein and having a dependent pivot pin provided at its front with a recess, a bearing for said pivot pin formed in said base or support and extending below said recess, a rock shaft extending transversely beneath the tongue in front of said 85 pivot pin and having two arms one of which projects into the recess in the pivot pin, a bolt engaging the other arm of said rock shaft, and a spring mounted upon said bolt for causing the rock shaft to exert pressure 90 upon the pivot of the tongue.

3. In a switch structure, the combination with a suitable base or support, of a tongue having a pivot pin dependent therefrom, a rock shaft extending transversely beneath 95 the tongue adjacent its heel and having an arm engaging the recessed pivot pin of said tongue and having at its outer end a horizontally disposed arm, and a vertically disposed bolt passing through said arm at the 100 outer end of the rock shaft to exert pressure upon the heel pivot of the tongue.

4. In a switch structure, the combination with a cast metal base or support and with a plate extending beneath and bolted thereto, of a tongue pivotally mounted in said base and having a depending pin provided with a recess having an inclined lower wall, a rock shaft journaled in said base and extending transversely beneath the tongue opposite said recess and having two arms one of which projects into said recess and the other of which is horizontally arranged at the outer end of said rock shaft, a vertically disposed bolt passing through the 110 other arm of said rock shaft and through said plate, and an adjustable nut and spring mounted upon said bolt.
